UNITED STATES PATENT OFFICE.

HENRY A. ROWLAND, OF BALTIMORE, MARYLAND.

MEANS FOR COOLING ELECTRIC CONDUCTORS.

SPECIFICATION forming part of Letters Patent No. 513,422, dated January 23, 1894.

Application filed February 14, 1893. Serial No. 462,301. (No model.)

To all whom it may concern:

Be it known that I, HENRY A. ROWLAND, a citizen of the United States, residing at Baltimore, in the State of Maryland, have invented certain new and useful Improvements in Means for Cooling Electric Conductors; and I do hereby declare the following to be a full, clear, and exact description of the invention, such as will enable others skilled in the art to 10 which it appertains to make and use the same.

My invention relates to methods of cooling conductors carrying large electrical currents, and the object of this invention is to so cool the conductors that they will not heat up 15 enough to destroy the insulation or cause other trouble. To accomplish this result, the conductors are made hollow so that a current of water or other fluid, either volatile or non-volatile, may be passed through the said conductors thereby cooling the same. In order 20 to allow the use of conducting fluid such as water, in the herein-described hollow conductors, a special device for breaking the water into drops, or into separate parts of larger 25 size, insulated from each other, is generally necessary, in order to prevent carrying off a large portion of the electricity by the conducting fluid. The same result may be accomplished by taking the conducting fluid 30 from an insulated tank, or conveying it to such a tank. In order to make the flow of the water or other conducting fluid continuous, a pair of tanks may be used, one of which is being emptied while the other is giving water to or receiving it from the electrified conductor. 35

Reference is had to the accompanying drawings, in which the same parts are indicated by the same letters throughout the several views.

Figure 1 represents a transformer of large size, the secondary coils being removed, and the primary coils being in the form of a hollow conductor through which a current of liquid is flowing. Fig. 2 represents a similar device to that shown in Fig. 1, except that the fluid flows from a tank through the primary coils of the transformer, and escapes as a spray as shown in Fig. 1. Fig. 3 represents a similar device to Fig. 2 except that the supply tank receives its liquid intermittently from

two feed tanks; the tank actually feeding being always insulated. Fig. 4 represents a device for operating the pair of feed tanks alternately and automatically so that the stream of water may at all times be broken. Fig. 5 55 represents another device for breaking up the stream of water into a spray. Fig. 6 represents a side elevation, and Fig. 7 a section, on the line $x-x$ of Fig. 6, of a revolving stop cock for breaking up the stream of water into separate segments. 60

A represents the laminated iron forming the core of the transformer, and B and B' represent the primary coils which carry a large current of electricity. These coils are hollow 65 and have forced through them the cooling fluid, preferably water, although any other liquid, either volatile or non-volatile, conducting or non-conducting, may be used.

In the device shown in Fig. 1, the cooling 70 fluid comes through the pipe C and flows through the branches c and c', forming the lower portion of the primary coil, up through the coils B and B', the pipes b and b', and the sprays or roses D and D' respectfully. By 75 means of these sprays or roses, the fluid is broken up into a number of drops, which are insulated from each other by the intervening particles of air, and thus do not carry off the electricity, or any material part thereof flowing through the coils B and B'. The electricity flows from the positive terminal E and binding post d through the coil B, the conductors c and c', the coil B', and the opposite binding post d to the negative terminal E'. 80

In the device shown in Fig. 2 the flow of electricity is as before, but the water or other fluid comes from a pipe K and a spray D³ by which it is broken up into insulated portions before it falls into the tank H. From this 90 tank it flows through the hollow conductor b², the coil B, conductors c², the coil B', the conductor b³, and the spray D², where it is again broken up, and thus prevented from carrying off any appreciable amount of electricity in the primary coils. 95

In the device shown in Fig. 3, the flow of electricity and of cooling fluid is the same as in Fig. 2, but the tank H is fed alternately from the tanks M and M', which receive their 100

water or other fluid from the pipe N. The cocks n and n', and m and m' are so adjusted by hand that the tank actually feeding the tank H, as M, is cut off from the pipe N, while 5 the other tank M' is cut off from the tank H while receiving fluid from the pipe N. In this way, the pipe N is always insulated from the tank H, and thus there is no chance for the electricity to escape through the conducting fluid.

To avoid manipulating the various cocks m, m', and n and n' shown in Fig. 3, either of the devices shown in Figs. 4 or 5 may be adopted.

15 In Fig. 4 the cocks n and n' are alternately operated by connecting rods m⁶ connected to arms m⁵ at the rear end of the shovel-shaped tanks M² and M³ which are pivoted at m² and m³, and are connected together by rods m⁷ pivoted to each tank at m⁸. These tanks M² and M³ have a sloping side m⁴ so arranged that when the water rises above a predetermined height, the tank tilts over and empties itself. As one tank, such as M², is tilted to 25 the position shown in Fig. 4, the cock n is closed and the tank M³ is thrown into the horizontal position, and the cock n' is opened. As soon as the tank M³ is ready to tilt the tank M² is righted and the valve n' closed, 30 and the cock n opened, by the tilting of the said tank M³. In this manner the said tanks M² and M³ will alternately fill and empty themselves automatically, and the tank will never be in fluid connection with pipe N.

35 In order that electrical connection may not be had through the apparatus, the arms m⁵ and the connecting rods m⁶ and m⁷ should preferably be of wood or other insulating material.

40 In the device shown in Fig. 5, the tank H is fed from the pipe N by means of the pipe K', and rotating sprinkler k, which latter may be of any well-known construction.

In Figs. 6 and 7 the pipe N is connected to 45 a stop cock P, provided with a rotating valve P' having one or more passages p². Only one of such passages is shown but it will be observed that the number of them may be multiplied if desired. This valve P' is attached 50 to a spindle p³ which is driven by the pulley p⁴, but any other convenient means for revolving the valve P' may be adopted. It will be seen that each time the passage p² is in 55 line with the pipe N and the hollow piston p of the spout, a jet of water will pass through the spout which will be intermittently formed and broken, allowing a series of segments of fluid to escape, which segments will be separated from each other by the intervening particles of non-conducting air.

60 While I have shown various methods of breaking up the conducting fluid into non-conducting or insulated parts, it will be obvious that many other methods might be adopted which could be used without departing from the spirit of my invention.

Having thus described my invention, what

I claim, and desire to secure by Letters Patent of the United States, is—

1. The method of cooling hollow conductors 7c carrying electric currents, which consists in passing a conducting fluid through said conductors, and in breaking the electrical continuity of said fluid after it leaves said conductor. 75

2. The method of cooling hollow conductors carrying electric currents, which consists in passing water through said conductors, and in breaking the electrical continuity of said water after it leaves said conductor. 80

3. The method of cooling hollow conductors carrying electric currents, which consists in passing a conducting fluid through said conductors, and in breaking the electrical continuity of said fluid before it reaches and after it leaves said conductor, substantially as 85 and for the purposes described.

4. The method of cooling hollow conductors carrying electric currents which consists in passing water through said conductors, and 90 in breaking the electrical continuity of said water before it reaches and after it leaves said conductor, substantially as and for the purposes described.

5. The combination of a hollow conductor 95 carrying electric currents, a conducting fluid passing therethrough, and means for separating said fluid into parts which are insulated from each other, substantially as and for the purposes described.

6. The combination of a hollow conductor adapted to carry large electric currents, a conducting fluid passing through said conductor, and means for breaking the electrical continuity of said fluid after it leaves said conductor, substantially as described. 100

7. The combination of a hollow conductor adapted to carry large electric currents, a conducting fluid passing through said conductor, and means for breaking the electrical continuity of said fluid before it reaches and after it leaves said conductor, substantially as 110 and for the purposes described.

8. In a transformer, the combination with the iron core, of a coil mounted on said core 115 composed of a hollow conductor, a conducting fluid passing through said hollow conductor, and means for separating said fluid after it leaves said conductor into parts insulated from each other. 120

9. In a transformer, the combination with the iron core, of a coil mounted on said core composed of a hollow conductor, a conducting fluid passing through said hollow conductor, and means for separating said fluid 125 before it reaches and after it leaves said conductor into parts insulated from each other.

In testimony whereof I affix my signature in presence of two witnesses.

HENRY A. ROWLAND.
